UNITED STATES PATENT OFFICE.

MAX LANGER, OF HERMSDORF, NEAR BERLIN, GERMANY, ASSIGNOR TO AUTOMATIC ELECTRIC COMPANY, OF CHICAGO, ILLINOIS.

AUTOMATIC TELEPHONE SYSTEM.

Application filed September 3, 1921. Serial No. 498,178.

(GRANTED UNDER THE PROVISIONS OF THE ACT OF MARCH 3, 1921, 41 STAT. L., 1313.)

To all whom it may concern:

Be it known that I, MAX LANGER, of Hermsdorf, near Berlin, Rodernstrasse 58, Germany, a German citizen, have invented certain new and useful Improvements in Automatic Telephone Systems (for which I have filed applications in Germany, filed 23, 10, 1915, Pat. No. 300,949, granted December 28, 1916; Austria, filed 21, 10, 1916, 10 Pat. No. 75,594, granted February 28, 1918; Denmark, filed 4, 7, 1916, Ser. No. 926—16; Czechoslovakia, filed April 16, 1921, re-validation of Austrian Patent 75,594, granted May 10, 1921), of which the following is a 15 specification.

The subject of the invention is a circuit arrangement for telephone systems with primary call seekers and secondary pre-selectors each call seeker and pre-selector forming a selecting pair and operating simultaneously.

With such circuit arrangements it may occur that a pre-selector finds a free switching position (e. g. in automatic telephone systems a free first selector) before the call seeker associated with the pre-selector has completed its setting operation. The result of this is that, although the pre-selector has taken into use a free switching position and 20 has marked it engaged, this position is again rendered free, because the speaking line has not been switched through at the call seeker and therefore the relays in the speaking line do not operate at the switching position, the 25 result being that the same conditions exist as though the receiver had been replaced at the calling station at the end of the conversation. The switching position being no longer marked engaged, the pre-selector is 30 left free to advance further. This is followed by the disconnection of the test relay of the pre-selector; and since the switching position is now apparently free again, this 35 relay can operate once more and the switching position may again be taken into use. This cycle is repeated until the call seeker has reached the calling line, or the line relays operate at the switching position. On the 40 other hand, a further rotation of the pre-selector to another free switching position may follow the first disconnection of the test relay, the pre-selector being then released again and rotated further—which

operation may be repeated until the call seeker has completed its setting. It may also 55 happen that during the re-energizing of the testing relay, the test relay of another pre-selector that is in motion and has just reached the switching position operates, whereby two calling subscribers may be connected up to one and the same switching position.

This defect is prevented according to the invention, by the arrangement that, when a free switching position is taken into use by 60 a pre-selector, devices are brought into operation at the selecting pair for the time during which the call seeker associated with the pre-selector is still performing its setting movement, which devices block an engaged 65 switching position and hold the pre-selector in the set position.

The drawing illustrates a circuit arrangement according to the invention, in which the selecting pair simultaneously started by 70 the starting relay C, consists of a call seeker AS acting as the primary pre-selector switch, and of a pre-selector VW acting as the secondary pre-selector switch. The switching position taken into use by the pre-selector is 75 marked engaged by a resistance w, which may be bridged across the two speaking leads. The circuit is so arranged that if the call seeker has completed its setting operation before the pre-selector has done so, the 80 speaking leads will not be bridged by the resistance w. This resistance, which is preferably about equal to that of the calling subscriber's line, is only connected up when the pre-selector has completed its setting sooner 85 than the call seeker, and in fact as soon as the switching relay V operates at the call seeker to switch it through to the speaking line.

The arrangement operates in the following manner:

When the subscriber takes down his receiver at the calling station, the calling relay R operates and prepares at contact 1 a circuit for the cut-off relay T and for the test relay Pa of the call seeker. At the same time it closes at contact 2, a circuit for the starting relay C of the selecting pair (earth, battery, relay C, contact 18, line 20, contact 2, earth) which at 3 connects up the rotary magnet Da of the call

seeker, and at 4 connects up the rotary magnet D_v of the pre-selector VW , so that both the call seeker AS and the pre-selector VW begin to rotate. Moreover, by closing the 5 contact 5, the starting relay C prepares the circuit for energizing the test relay P_a and the cut-off relay T , and at 6 it prepares the circuit for energizing the test relay P_v and the engaging relay C' . As soon as the call 10 seeker AS reaches the calling line, the relays P_a and T operate (earth, battery, relay T , contact 1, test wiper of the call seeker AS , test relay P_a , contact 5, earth). The cut-off relay T , by opening contacts 7 and 15 8, disconnects the calling relay R from the calling line, so that R releases and opens the contacts 1 and 2. The cut-off relay T has however closed the contact 9, thereby locking itself and the test relay P_a , in a 20 circuit independent of the calling relay R . The test relay P_a at contact 10 short-circuits its high-resistance winding, thus blocking the calling line, and by opening the contact 11, breaks the circuit of the rotary 25 magnet D_a , so that the call seeker AS remains stationary. The test relay P_a also switches the line through at 12 and 13. As soon as the pre-selector VW reaches a free 30 primary selector GW_1 the testing relay P_v and the engaging relay C' operate (earth, battery, relay P_v , contact 6, testing arm of the pre-selector VW , contact m , relay C' normal contact kl , earth). The test relay P_v short circuits its high-resistance winding at 35 14, and prevents the selector GW_1 being taken into use by another pre-selector. Also, by opening the contact 15, the test relay P_v disconnects the rotary magnet D_v , so that the pre-selector is stopped. The test relays 40 P_a , P_v at 16 and 17 connect up the switching relay V which at 19 switches the starting lead through to the next pair of pre-selecting switches. By closing the contacts 21, 22, the relay V also switches the speaking line through, so that the line relays 45 A , B at the selector GW_1 are energized, the relay A being the impulse relay while relay B controls the release. At contact 23, the relay B keeps open the circuit of the 50 release magnet M .

If, contrary to the foregoing assumption, the pre-selector is brought to a standstill sooner than the call seeker AS , then the resistance w is bridged across the speaking 55 leads at 24, 25 by the relays C and P_v , so that the line relays A , B are energized (earth, battery, relay A , contact p , pre-selector VW , contact 24, resistance w , contact 25, pre-selector VW , contact p , relay B , earth).

B opens at 23, the circuit for the release magnet M . When the call seeker AS subsequently reaches the calling line, the testing relay P_a operates and with the test relay 60 P_v , connects up the relay V at 16 and 17.

Relay V at contact 18 disconnects the starting relay C , which on deenergizing, opens its contact 24, so that w is disconnected at the same time. However, since the relay V switches the speaking line through at 21, 70 22, the relay B does not release.

If the bridge w were not connected up, the relays A and B could not be energized when the pre-selector VW reaches the selector GW_1 , until the call seeker reached 75 the calling line, and during that interval the following operations would take place.

On the pre-selector reaching a free selector, the relays P_v and C' operate. C' connects up the release magnet at 23c', 80 and the latter by opening its contact m , breaks the circuit of P_v and C' . The engaging relay C' again disconnects the release magnet M , so that the contact m again closes the circuit of C' and P_v and the cycle 85 of operations is repeated. If now, during the time P_v operates anew, pre-selector VW reaches the selector GW_1 , the test relays P_v of both pre-selectors operate at the same time, thus causing the selector to be taken 90 into use from two directions and causing wrong connections.

What I claim and desire to protect by Letters Patent is:

1. In a telephone system, a selector switch, 95 talking conductors terminating in said switch, a hunting switch having line wipers for connecting with said conductors, means for thereafter connecting the conductors of a calling line with said wipers, and means 100 for bridging said wipers until the calling line is connected.

2. In a telephone system, a selector switch, talking conductors terminating in said switch, a hunting switch having movable 105 contacts for connecting with said conductors, means for operating said hunting switch over a calling line and for connecting the conductors of said line with said movable contacts, a line relay in said selector, a local circuit for said line relay closed over one of said talking conductors when the hunting switch is operated, a control circuit for said line relay closed when the calling line is connected to said movable contacts, and 110 means for then opening said local circuit.

3. In a telephone system, a calling line, a selector switch, backward and forward hunting switches linked together and operating contemporaneously for connecting with 120 said line and switch, respectively, talking conductors extending through said switches, and means in said forward hunting switch effective in case the said selector is found first for closing a bridge across the talking 125 conductors.

4. In a telephone system, a calling line, a selector switch, backward and forward hunting switches linked together and operating contemporaneously for connecting 130

with said line and switch, respectively, talking conductors extending through said switches, means in said forward hunting switch effective in case the said selector is found first for closing a bridge across the talking conductors, and means for opening said bridge when the calling line is found.

5. In a telephone system, a calling line, a selector switch, backward and forward hunting switches linked together and operating contemporaneously for connecting with said line and switch, respectively, a controlling line relay in said selector, and means in said forward hunting switch effective in case said selector is found first for closing a local circuit for said line relay.

6. In a telephone system, a calling line,

a selector switch, backward and forward hunting switches linked together and operating contemporaneously for connecting with said line and switch, respectively, a controlling line relay in said selector, means in said forward hunting switch effective in case said selector is found first for closing a local circuit for said line relay, and means effective when the calling line is found for substituting a new circuit including the calling line for said local circuit. ²⁰

Signed by me at this 15th day of August, 1921.

MAX LANGER.

In the presence of—

GUSTAV THICLE,
HEINRICH EHWALD.
